UNITED STATES PATENT OFFICE.

LEE DE FOREST, OF NEW YORK, N. Y., ASSIGNOR TO RADIO TELEPHONE & TELEGRAPH COMPANY, A CORPORATION OF DELAWARE.

WIRELESS-TELEPHONE TRANSMITTING SYSTEM.

1,125,496.

Specification of Letters Patent. Patented Jan. 19, 1915.

Application filed September 17, 1910. Serial No. 582,449.

To all whom it may concern:

Be it known that I, LEE DE FOREST, a citizen of the United States, residing in the city, county, and State of New York, have made a certain new and useful Invention in Wireless-Telephone Transmitting Systems, of which the following is a specification.

This invention relates to wireless telephone transmitting systems.

10 The object of the invention is to provide a wireless telephone transmitting system which is simple in construction and arrangement, and efficient in operation.

15 A further object is to provide a system of the nature referred to wherein the telephone transmitter is associated with a high frequency circuit of the system, and wherein a source of alternating or interrupted current is employed.

20 A further object is to provide a system of the nature referred to wherein the telephone transmitter is arranged and operates to throw the high frequency oscillations of the antenna and primary oscillating circuits more or less out of tune with each other.

25 A further object is to provide a system of the nature referred to wherein the relative inductance of the antenna and primary oscillating circuits is varied in the transmission of speech.

30 A further object is to provide a system of wireless telephony employing a radiotone or quenched spark system of excitation of high frequency oscillations.

35 A further object is to provide a system of wireless telephony employing slowly damped radiated waves.

40 Other objects of the invention will appear more fully hereinafter.

45 The invention consists substantially in the construction, arrangement, and relative location of parts all as will be more fully hereinafter set forth, as shown in the accompanying drawings and finally pointed out in the appended claims.

50 In the drawings,—Figure 1 is a view in diagram showing a circuit arrangement in a system embodying my invention, and wherein the telephone transmitter is arranged to more or less short circuit part of the inductance in the high frequency circuit of the antenna system, as, for instance a coil of the coupling system. Fig. 2 is a

similar view wherein the telephone transmitter is arranged to short circuit more or less of an extension of a coil in the antenna coupling system. Fig. 3 is a similar view wherein the telephone transmitter is associated inductively with a coil of the coupling system. Fig. 4 is a similar view wherein the telephone transmitter is associated directly in the antenna earth circuit. Fig. 5 is a similar view wherein the telephone transmitter is associated with an extra inductance coil in primary high frequency oscillating circuit. Fig. 6 is a detail diagrammatic view of a microphone or telephone transmitter circuit suitable for use in connection with my invention. Fig. 7 is a view in diagram showing a quenched or series spark gap and with the microphone connected across a portion of said gaps.

55 In carrying out my invention I propose to employ a source of alternating or interrupted current having a frequency of alternation or interruption within the upper limit of audibility and yet sufficiently high to prevent the hum thereof from unduly interfering with voice transmission. I have found a source of alternating current having a frequency within the upper limit of audibility and above four hundred cycles

60 per second, sufficient and satisfactory for my purposes. From this source of alternating or interrupted current, and when I hereinafter refer to "alternating" current I

65 wish also to include thereby "interrupted" current, I propose to excite high frequency oscillations of the character required for generating electro-magnetic radiation for

70 space communication. I have found that the radiotone system of excitation well answers my purpose; that is, a system of shock excitation such as is accomplished by

75 the quenched spark or singing spark method, although in this respect my invention as defined in the claims is not to be limited or restricted. The radiotone

80 system, however, possesses the advantage of effecting the radiation of slowly damped waves which are particularly suitable for my purposes. I also propose, in accordance with the principles of my invention, to

85 associate the microphone or other telephone transmitting device with a high frequency circuit of the system. This association with

the high frequency circuit may be accomplished in various ways. For instance, the microphone may be so arranged that changes in the resistance of the microphone, caused by the voice or other sounds falling on the diaphragm thereof, introduces variations in a short circuit around more or less of the coils of the high frequency helix. This may be a coil of the coupling system, thereby varying the inductance of the antenna system. This short circuiting arrangement of the microphone may be accomplished with reference to an extension of such high frequency helix or coupling coil, or the microphone circuit may be inductively associated with some convenient part of a high frequency circuit, as, for instance, with the high frequency helix or coupling coil; or it may be associated with an extra coil in the primary oscillating circuit, or it may be located directly in the antenna earth circuit, although generally, in this latter case the power employed should be comparatively small otherwise the current through, and the sparking in, the microphone, might tend to injure the same. In all cases the microphone, in accordance with my invention, should be associated with some part of a high frequency circuit, having the characteristics above pointed out, and the association should be such that variations of resistance in the microphone circuit due to sound vibrations impinging on the diaphragm of the microphone, cause corresponding variations in the inductance of the high frequency circuit with which the microphone is associated, the high frequency oscillations being excited by an alternating or interrupted current having a frequency below the upper audible limit, and above, say, four hundred cycles per second. These variations cause the antenna and primary high frequency oscillating circuits to be thrown more or less out of tune with each other, thereby correspondingly modifying the slowly damped radiated waves.

By employing the radiotone, quenched or singing spark system of excitation of the high frequency oscillations, a plurality of gaps are used in series in the primary high frequency oscillating circuit, thereby attaining a quick quenching of each spark discharge and a resulting shock excitation, and the radiation of slowly damped waves.

Referring to Fig. 1, A designates the antenna, E its earth connection, and B an alternating or interrupted current source, such for instance, as an alternating current generator of a frequency of at least four hundred cycles per second. The current source B is connected with the oscillating circuit in suitable manner, as through a step-up transformer F. The oscillating circuit contains the usual capacity, as condenser C, and inductance, in series, and has the "discharger"

multiple spark gap D, connected across said circuit. The oscillating circuit may be associated with the antenna system in any suitable and well known manner. I have shown an adjustable conductive coupling 70 for this purpose. In a generating and radiating system such as above described the oscillations in the antenna system are shock excited, each spark discharge being quickly quenched, the air gaps or spaces between 75 the plates or disks constituting and forming the spark gap structure enabling this result to be accomplished, and by reason of the quick quenching of the spark following each discharge, and the high resistance resulting from the multiple gaps in the discharger, there is no reflex action from the antenna system back into the primary oscillating circuit. The result is the radiation of slowly damped waves having an intensity and capable of carrying the radiations through extended distances and, by reason of the modifications imposed thereon by the sound waves impinging upon the telephone transmitter or microphone associated with 90 one of the high frequency circuits of the system, capable of being utilized for the transmission of articulate speech. In Fig. 1 the modifications of the radiated waves, by and in accordance with sound waves, is 95 accomplished by associating the microphone or telephone transmitter M with the coupling coil or high frequency helix G constituting part of the conductive coupling between the antenna system and the primary high frequency oscillating system, in such relation as to more or less short circuit part of such helix or coil, thereby enabling changes in the resistance in the telephone transmitter or microphone due to 100 sound waves impinging upon the diaphragm thereof to effect a variation in the inductance of the antenna system.

In Fig. 2 I have shown the microphone or telephone transmitter M associated with an extension H of the coil G in such relation and adjustable connection therewith as to short circuit more or less of such extension, thereby providing means for modifying the inductance of a high frequency circuit by and in accordance with the sound waves accompanying articulate speech.

In Fig. 3 I have shown the microphone or telephone transmitter M associated inductively with coil G.

In Fig. 4 I have shown the microphone M located directly in the antenna earth circuit. When this arrangement is employed, however, the power used should be small in order to prevent the current and sparking in the microphone from injuring or destroying such microphone.

In Fig. 5 I have shown an extra inductance or coil J in the primary high frequency oscillating circuit, the micro-

phone M being shunted around and adjustably connected to said coil.

If desired and as indicated in Fig. 6 the circuit L' of the microphone M' may contain 5 a condenser C'.

The radiated waves modified by or in accordance with the sound waves accompanying articulate speech, in the manner above set forth may be received at a receiving 10 station by any suitable or well known arrangement of wireless receiving system, and the oscillations generated in the receiving system by the modified waves, utilized for reproducing or in reproduction of the 15 sound waves employed to effect the initial modifications.

While I have shown and described various arrangements embodying my invention, and various manners of association of the 20 microphone or telephone transmitter with a high frequency circuit, or portion thereof supplied from an alternating or interrupted current source, my invention, as defined in the claims, and in their broadest scope, is 25 not to be limited or restricted to the exact arrangement shown.

Fig. 7 shows an arrangement by which the microphone acts to more or less short circuit a portion of the series spark gaps. 30 I find that if four gaps in series be employed it is satisfactory to connect the microphone across two of these gaps. But

Having now set forth the object and nature of my invention and various constructions embodying the principle thereof, what 35 I claim as new and useful and of my own invention and desire to secure by Letters Patent is,—

1. A wireless telephone transmitting system, including a source of alternating current supply having a frequency below the upper audible limit, and a multiple spark gap, and means for modifying the radiated waves from such system by and in accordance 40 with sound waves.

2. A wireless telephone transmitting system including a source of alternating current supply to a quenched spark gap, the alternating current having a frequency below 50 the upper audible limit, in combination with means for modifying the generated oscillations by and in accordance with sound waves.

3. In a wireless telephone transmitting system, an oscillating circuit including a quenched spark gap, an antenna circuit associated with said oscillating circuit, and a source of alternating current supply for said

oscillating circuit, in combination with a telephone transmitting device associated 60 with one of said circuits and arranged to vary the inductance thereof by and in accordance with sound waves.

4. In a wireless telephone transmitting system, an oscillating circuit including a 65 quenched spark gap, an antenna circuit associated with the oscillating circuit, and a source of current supply for the oscillating circuit, in combination with means for modifying the generated oscillations by and 70 in accordance with sound waves and including means for varying the inductance in one of said circuits.

5. In a wireless telephone transmitting system, an oscillating circuit including a 75 quenched spark gap, an antenna circuit associated with said oscillating circuit, and a source of alternating current supply for said oscillating circuit, said alternating current supply having a frequency below the upper 80 audible limit and above four hundred cycles per second, and means associated with one of said circuits for modifying the oscillations therein by and in accordance with sound vibrations and including means for 85 varying the inductance in one of said circuits.

6. A wireless telephone transmitting system, having means for radiating slowly damped waves of audible group frequency, 90 and means for modifying the radiated waves by and in accordance with sound vibrations.

7. A wireless telephone transmitting system for radiating slowly damped waves of 95 audible group frequency and including a high frequency circuit, and a telephone transmitter device associated with said circuit to modify the oscillations therein by and in accordance with sound vibrations. 100

8. A wireless telephone transmitting system for radiating slowly damped waves at audible group frequency and including a high frequency circuit, in combination with a telephone transmitter device arranged to 105 vary the inductance of said high frequency circuit by and in accordance with sound vibrations.

In testimony whereof I have hereunto set my hand in the presence of the subscribing 110 witnesses, on this 9th day of September A. D. 1910.

DISCLAIMER.

1,125,496.—*Lee de Forest, New York, N. Y.* WIRELESS-TELEPHONE TRANSMITTING SYSTEM. Patent dated January 19, 1915. Disclaimer filed April 24, 1916, by the assignee, *De Forest Radio Telephone & Telegraph Co.*

Enters this disclaimer—

“To that part of the claim in said specification, being claims 1, 2, 6, and 7, which is in the following words, to wit:

“1. A wireless telephone transmitting system, including a source of alternating current supply having a frequency below the upper audible limit, and a multiple spark gap, and means for modifying the radiated waves from such system by and in accordance with sound waves.

“2. A wireless telephone transmitting system including a source of alternating current supply to a quenched spark gap, the alternating current having a frequency below the upper audible limit, in combination with means for modifying the generated oscillations by and in accordance with sound waves.

“6. A wireless telephone transmitting system, having means for radiating slowly damped waves of audible group frequency, and means for modifying the radiated waves by and in accordance with sound vibrations.

“7. A wireless telephone transmitting system for radiating slowly damped waves of audible group frequency and including a high frequency circuit, and a telephone transmitter device associated with said circuit to modify the oscillations therein by and in accordance with sound vibrations.”
